Thomas F. Moroney, Jr., Shrewsbury, Mass.

Application December 5, 1957, Serial No. 48,788

Term of patent 14 years

(Cl. D14—3)

FIG.1

FIG.2

FIG. 3

FIG. 4

Fig. 1 is a top plan view of a motor vehicle embodying my new design;

Fig. 2 is a side elevational view;

Fig. 3 is a rear elevational view, and

Fig. 4 is a front elevational view showing my new design.

The essential features of my design reside in those portions shown in full lines. The broken lines portions have been omitted in part or entirely from some of the views for convenience of illustration.

I claim:

The ornamental design for a motor vehicle, as shown and described.
